UNITED STATES PATENT OFFICE.

GEORGE H. DAVIS, OF PROCTOR, VERMONT.

MACHINE FOR SAWING STONE.

SPECIFICATION forming part of Letters Patent No. 759,422, dated May 10, 1904.

Application filed September 19, 1902. Serial No. 124,084. (No model.)

To all whom it may concern:

Be it known that I, GEORGE H. DAVIS, a citizen of the United States, residing at Proctor, in the county of Rutland and State of Vermont, 5 have invented a certain new and useful Improvement in Machines for Sawing Stone, of which the following is a full, clear, and exact description.

This invention relates to machines for sawing stone, and more especially to that class of such machines in which a frame has mounted in it one or more blades or saws and to which a reciprocating motion is imparted. As heretofore constructed these frames have been 15 hung from sway-bars by pin-joints connecting the hangers both to the frame and to the sway-bars, and in operation there is thus a fixed or constant radius of movement of the blades or saws, the point of contact between the saws 20 and stone being only at the lowest point of the arc described by the saws.

In the present invention I provide yielding joints in addition to the pin-joints and arrange the hangers in the sway-bars with a sliding 25 connection, so that the radius of movement is constantly varying as the frame is reciprocated, thus regulating and equalizing the pressure on the stone and where sand or other abrasive material is used permitting it to get 30 more easily under the saws, and so expedite the cutting, all as I will proceed now more particularly to set forth and finally claim.

In the accompanying drawings, illustrating 35 my invention, in the several figures of which like parts are similarly designated, Figure 1 is a side elevation of sufficient of an ordinary form of sawing-machine to show my improvement. Fig. 2 is an elevation of the right-hand end of Fig. 1. Fig. 3 is a sectional elevation 40 showing the details of the improvement. Fig. 4 is a top plan view of the sway-bar with the hanger in cross-section. Fig. 5 is a longitudinal section and partial elevation of a modified form of yielding joint. Fig. 6 is a diagram 45 illustrating the theoretical movement of the frame with fixed pin-joints. Fig. 7 is a diagram illustrating the theoretical movement of the frame with yielding connections with the sway-bars.

The machine-framing, saw-frame, and adjusting and reciprocating mechanisms for the saw-frame are here shown of approved construction and need no description.

The saw-frame 1 is provided with pin-lugs 2, and the sway-bar 3 is connected with the sliding bearing-blocks 4 in any usual manner. The hangers 5 have eye-bearings 6, which are applied to the pin-lugs 2 on the saw-frame, and these hangers extend through tubes 7, fixed in the sway-bars, each hanger having a yielding device—such as a coiled or other spring, block of rubber, air or fluid cushion or equivalent—interposed between its lower end and the tube. In Figs. 1 to 4 this yielding device is shown as a coiled spring 8, mounted upon a spring-seat plate 9, adjustably applied to the hanger by a nut 10 and expanding against a cap 11, whose movement is limited by contact with the tube. The tube may be closed by a plug 12, adjustably secured thereto by a coupling 13. 70 The hanger passes freely through the tube and sway-bar, and above the sway-bar it is provided with another and similar yielding device, shown as a coiled spring 14, expanding against a cap-plate 15, held to the hanger by nut 16 and seated in a plate 17, resting upon a plug 18, adjustably connected with the tube by a coupling 19. The plugs 12 and 18 serve also as guides for the moving hangers as they slide up and down relatively to the sway-bars. The 75 force of the springs 8 and 14 may be regulated with the nuts 10 and 16.

The two hanger-tubes at each end are connected and braced by adjustable straining-bars 20, spreading from the sway-bars, or they 80 may be otherwise held in place.

As one substitute for the coiled spring I have shown in Fig. 5 a fluid or air pressure cylinder 21, suspended from the sway-bar 22 by a rod or tube 23 and having a piston-head 90 24 applied to the hanger 25, which otherwise may be as usual. In such case there need be no yielding connection immediately with the sway-bar.

As indicated by the diagram Fig. 6, where 95 the radius is constant, the saw-frame moves in an arc of a circle; but as indicated in Fig. 7 the yielding joints provide a variable radius.

Thus the arc *a* indicates the motion of the frame before the saws strike the stone. The horizontal line *b* between the radii *c d* indicates the travel of the saws across the stone, 5 during which period the radius is continually varying under the action of the springs, it being shortest on the line *e*, and after the line *d* is reached the longest available radius controls, and thereafter there is another arc 10 of a circle *f* described. The return movement from right to left is merely a repetition in reverse of the movements described, and hence there is a rise at each end of the stroke.

The springs above the sway-bar are used 15 principally for steadyng the gang at the ends of the stroke. The springs at the lower ends of the hangers are for increasing slightly the pressure of the saws on the stone during the stroke and also for steadyng the motion of 20 the gang at the ends of the stroke. The two sets of springs together prevent excessive jumping of the frame at the end of the stroke, but permit vibration enough to allow the abrasive material to pass under the saws 25 freely. The two springs work together, so that when the gang is high in the frame—that is, when the position of the gang is above the level of the crank-shaft, so that the pitman is working on an angle with the horizontal 30—the lower spring at the pitman end of the frame is very much compressed on the upstroke and the upper spring is compressed on the downstroke. By having the springs on both sides of the sway-bar the "jump" of 35 the sway-bar is decreased, while the raise of the frame is retained sufficiently to let the sand work under the blades.

The invention is equally applicable to saws with or without teeth or other cutting-surfaces and with or without the use of water 40 and an abrasive.

What I claim is—

1. A stone-sawing machine, having a saw-frame, hangers therefor, sway-bars, and yielding connections for the hangers and sway-bars arranged upon opposite sides of the sway-bars. 45

2. A stone-sawing machine, having a reciprocating saw-frame, hangers to which the saw-frame is jointed, sway-bars having fixed 50 depending portions with which the hangers are slidably connected, and yielding devices interposed between the hangers and their sway-bar connections.

3. A stone-sawing machine, having a reciprocating saw-frame, hangers to which the saw-frame is jointed, sway-bars having fixed 55 depending portions with which the hangers are slidably connected, and springs interposed between the hangers and their sway-bar connections. 60

4. A stone-sawing machine, having a reciprocating saw-frame, sway-bars provided with fixed depending tubes, hangers attached to 65 said saw-frame and extending up through said tubes, and yielding devices interposed between said tubes and hangers, whereby the radius of movement of the hangers is varied. 70

5. A stone-sawing machine, having a reciprocating saw-frame, sway-bars provided with 75 fixed depending tubes, hangers attached to said saw-frame and extending up through said tubes, and coiled springs interposed between said tubes and hangers, whereby the radius of movement of the hangers is varied. 75

In testimony whereof I have hereunto set my hand this 11th day of September, A. D. 1902.

GEORGE H. DAVIS.
